J. M. MULL

STRIKER AND JOINTER

Filed May 4, 1922

Inventor
Joseph M. Mull

Hardway & Lathay
Attorneys

UNITED STATES PATENT OFFICE.

JOSEPH M. MULL, OF HOUSTON, TEXAS.

STRIKER AND JOINTER.

Application filed May 4, 1922. Serial No. 552,397.

To all whom it may concern:

Be it known that I, JOSEPH M. MULL, citizen of the United States, residing at Houston, in the county of Harris and State 5 of Texas, have invented certain new and useful Improvements in Strikers and Jointers, of which the following is a specification.

This invention relates to new and useful improvements in a brick layer's striker and 10 jointer.

One object of the invention is to provide a tool especially designed for the purpose of finishing the cement joints between the brick, in the work of brick laying.

Another object of the invention is to provide a simple tool of the character described which may be cheaply constructed and easily 15 handled.

With the above and other objects in view 20 the invention has particular relation to certain novel features of construction, arrangement of parts and use, an example of which is given in this specification and illustrated in the accompanying drawings, wherein:—

Figure 1 shows a plan view of the device. 25 Figure 2 shows a side view, and

Figure 3 shows a side view of a modified form of runner employed.

In the drawings the numeral 1 designates 30 the handle which is formed into a convenient grip. One end of this handle is formed with the neck 2 whose free end is formed into a bearing 3 designed to receive an ordinary nail which is passed upwardly there- 35 through, and which is secured therein by means of a thumb screw 5 which is threaded through the bearing 3. The other end of the handle is reduced and outwardly threaded forming a spindle 6 provided to receive the 40 clamp nut 7. A runner 8 is provided whose ends are upwardly turned, and one of said upwardly turned ends 9 has a bearing which receives said spindle 6, said end being clamped by the clamp nut 7 between said 45 nut and the adjacent end of the handle. The bearing 3 has the laterally extending spin- 50 dles 10, 10 on which the bearing wheels 11, 11 are mounted to rotate. In the process of laying brick it is usually desirable to re-

move a certain part of the cement forming 50 the joint between the brick so as to give a better appearance to the finished structure. In order to do this the device herein described is employed and when used the bearings 11 run along the outer faces of the ad- 55 jacent brick, and the head of the nail 4 scrapes out the cement between the brick while it is in a plastic state. The imple- 60 ment is then reversed and the runner passes along said joint and smoothes down said ce- 65 ment giving a more perfect joint.

If it is desired the nail 4 and the runner 8 may be dispensed with and the form of runner shown in Figure 3 employed. This runner is indicated by the numeral 10 and is 65 formed with a shank 11' which may be in- 70 serted through the bearing 3, as illustrated in dotted lines in Figure 2, and held therein by the thumb screw 5. When this form of runner is employed the plastic cement of the 75 joint may be scraped out and smoothed at one stroke of the implement.

What I claim is:—

A device of the character described in- 75 cluding a handle formed into a grip, a de- 80 pending neck secured to one end of the han- 85 dle and whose free end is formed into a bearing, a striker formed with a shank which is fitted through said bearing, a thumb screw 90 threaded through said bearing and provided to secure said shank therein, laterally ex- 95 tending spindles carried by the bearing, bearing wheels mounted to rotate on said spindles, the other end of said handle being reduced, a runner whose ends are upwardly turned, one of said upwardly turned ends being formed into a bearing to receive the reduced end of the handle and a clamp nut threaded onto said reduced end to secure the 90 runner to the handle.

In testimony whereof I have signed my name to this specification in the presence of two subscribing witnesses.

JOSEPH M. MULL.
